OUTDOOR BARBECUE-OVEN COMBINATION

Robert Tarsitano, Jr., 305 E. Elm St.,
Lombard, Ill. 60148

Filed Mar. 27, 1972, Ser. No. 238,724

Term of patent 3½ years

Int. Cl. D7—02

U.S. Cl. D7—107

Fig. 1

Fig. 3.

FIG. 1 is a front perspective of the outdoor barbecue-oven combination with the upper door-table and lower draft door shown in open position;

FIG. 2 is a front elevation thereof;

FIG. 3 is a side elevation thereof as seen from the opposite side of FIG. 1;

FIG. 4 is a top plan view thereof;

FIG. 5 is a side elevation as seen from the opposite side of FIG. 3 with the door-table and draft door shown in open position; and

FIG. 6 is a rear elevation thereof.

The chimney covering element has been omitted in FIGS. 1, 4, 5, and 6 for convenience of illustration.

I claim:

The ornamental design for an outdoor barbecue-oven combination, as shown and described.
